INVENTOR:

James A. Cook

UNITED STATES PATENT OFFICE.

JAMES A. COOK, OF EAST BRIDGEWATER, MASSACHUSETTS.

GRIDIRON.

No. 890,219.

Specification of Letters Patent.

Patented June 9, 1908.

Application filed January 2, 1908. Serial No. 409,081.

To all whom it may concern:

Be it known that I, JAMES A. COOK, a citizen of the United States, residing at East Bridgewater, in the county of Plymouth and 5 State of Massachusetts, have invented a new and useful Improvement in a Gridiron, of which the following, taken in connection with the accompanying drawings, is a specification.

10 My invention relates to improvements in gridirons and consists chiefly in constructing it in easily detachable parts and in minor details for the purpose of rendering the same more practical and useful, the object being 15 to so construct a gridiron that it is easy to remove the cooked article from it and also to so construct it that it will not open accidentally. These objects I attain by the means shown in the accompanying drawings in 20 which—

Figure 1 is a view in perspective showing the instrument complete. Fig. 2 is a vertical longitudinal sectional view taken through the center, the two parts being closed together as when in use.

This gridiron is of the folding kind having two detachably attached leaves, a lower one and an upper one between which the article to be cooked is placed.

30 The lower leaf of the gridiron may be described as follows: The wire A, A¹, A³, A⁴, A forms a square frame having the parts of the wire that form the sides bent into corrugations as indicated at A² . . . A² which serves 35 to assist in keeping the article that is being cooked from sliding off. The wire B starts from the front wire A, A¹, to which it is attached, and passing to the back wire A³, A⁴ is turned around it and bent up to B¹, thence 40 it passes over (forming a loop) to B², thence around the back wire A³, A⁴, and then it becomes the bar B³, the terminal of which is attached to the front wire A, A¹. The handle wire starts at C from the back wire A³, A⁴ 45 of the frame, thence to the front wire of the frame and around it; thence it is bent up to one, C¹, of the catch standards C¹, C³, from the catch standard C¹ goes to the curve C², thence it loops back forming the second 50 catch standard C³, thence around the front wire and back to the rear wire at C⁴. It is to be observed that this last wire forms the handle for the lower leaf of the gridiron, the catch standards C¹ and C³ as well as the two 55 middle bars of lower leaf.

The upper leaf of the gridiron is made up as follows: The outside frame consists of

the wire D, D¹, D², D³. The wire E starts from the front wire D, D¹, to which it is attached, thence to and around the back wire 60 at E¹, thence upward to form the loop E², E³, thence downward and around the back wire at E⁴; thence to and around the front wire at E⁵; thence downward to form the holding start E⁶, thence up to E⁷, and parallel to the 65 wire D D¹ to E⁸, forming a loop to hold the handle H¹ of this leaf, thence downward to E⁹ forming a second start, thence back to the front wire D, D¹, to which it is attached at E. The central bars are formed by the wires F, 70 F¹, and F², F³. The handle H¹ has one of its branches attached to the back wire at H² and the other branch to the back wire at H.

The use of my gridiron may be set forth as follows: By turning up the upper leaf, by 75 using the handle H¹, the loop E², E³ of the upper leaf can be drawn out from under the loop B¹, B², attached to the lower leaf and thus the two parts may be easily separated and the article that has been cooked taken 80 off from the lower leaf. The starts E⁶, E⁹ pass inside of the front wire of the lower leaf and thus prevent the upper leaf from slipping towards the front when the leaves are closed, see Fig. 2. The catch standards C¹, 85 C³ have notches as shown and serve to engage with the handle H¹ and securely hold it when the gridiron is closed.

Claims.

A folding gridiron having detachable leaves, 90 each leaf having at its rear end a loop extending upward serving, singly, as guards for holding the article which is being cooked, and together as detachable hinge pieces; a loop extending upward from the front wire of the 95 upper leaf through which the wires of the handle of said leaf pass to the rear wire to which they are attached; the wires of the said handle are yieldingly held by the said loop; a handle attached to the lower leaf and 100 having notched standards, the notches being adapted to engage with the yielding wires of the handle of the upper leaf and holding the leaves at the desired distance apart; substantially as and for the purpose set forth. 105

In testimony whereof, I have signed my name to this specification in the presence of two subscribing witnesses, on this 28th day of December, A. D. 1907.

JAMES A. COOK.
